DESIGN FOR A COMBINATION PENCIL CONTAINER AND CLAMP

Claude W. Beardsley, San Diego, Calif.

Application February 21, 1936, Serial No. 61,281

Term of patent 14 years

To all whom it may concern:

Be it known that I, Claude Wm. Beardsley, a citizen of the United States, residing at San Diego, in the county of San Diego and State of California, have invented a new, original, and ornamental Design for a Combination Pencil Container and Clamp, of which the following is a specification, reference being had to the accompanying drawing, forming part thereof.

The figure is a perspective view of a combination pencil container and clamp, showing my new design, all the parts not in view being duplicative of those which are displayed in said view.

I claim:

The ornamental design for a combination pencil container and clamp substantially as shown and described.

CLAUDE WM. BEARDSLEY.
